SPINNING MACHINE FOR RAYON OR OTHER
SYNTHETIC MATERIAL

Julius Brenzinger, Fairfield, Conn., assignor to
The Max Ams Chemical Engineering Corpora-
tion, Bridgeport, Conn., a corporation of Con-
necticut

Application October 1, 1930, Serial No. 485,626

1 Claim. (Cl. 18—8)

The present invention relates generally to rayon, or other synthetic material, spinning machines and has for its main object and feature the coordination of the speed of the take-up spool with the speed of the pump that delivers the synthetic material to the spinnerette from which latter the thread-like product passes to said take-up spool.

In the accompanying drawings, the invention is disclosed in a concrete and preferred form in which:

Fig. 1 is a plan view more or less diagrammatic in character of the essential elements of a rayon spinning machine;

Fig. 2 is a view in side elevation of the novel transmission means associated with the rayon spinning machine;

Fig. 3 is a vertical sectional view substantially on the plane of line 3—3 of Fig. 2;

Fig. 4 is a detail view of the reversible ratchet and pawl mechanism; and

Fig. 5 is a horizontal sectional view substantially on the plane of line 5—5 of Fig. 4.

1 indicates a spinnerette to which synthetic material is supplied by pump 2. 3 is a rotatable spool and 4 is a thread-guide having a movement back and forth to lay the newly formed thread on the spool. As wound material 5 accumulates on the spool, the effective diameter of the spool increases and consequently it takes up more and more thread per revolution. The speed of the pump being constant, it will be understood that the thread produced becomes thinner and thinner. In an application filed May 9, 1930, Ser. No. 450,950, means are shown whereby, as the wound material accumulates on the spool, the speed of the pump, and consequently the rate of delivery of the synthetic material, is increased to the end that the thread produced may be of uniform thickness or denier. In the present application the reverse arrangement is disclosed, viz: a construction in which the pump speed remains constant and the angular speed of the spool is gradually decreased to compensate for its increase in surface speed.

6 indicates a motor or other source of power from which motion is transferred to main shaft 7 by means of flexible connection 8. 9 and 10 indicate two driven shafts, provided with pulleys 11 and 12 having faces that move toward and away from each other. Main shaft 7 is provided with a pulley 13 the faces of which need not be movable, and passing over pulleys 11, 12 and 13 is a belt or flexible transmission member 14. 55 Levers indicated at 15 and 16 are pivotally sup-

ported at 17 midway their ends, and these levers are pivotally connected at 18 and 19 to the opposed faces of pulleys 11 and 12. The free ends of the levers are connected by spring 20, the action of which latter normally tends to separate the faces of pulley 11 and to bring toward each other the faces of pulley 12. Suitable means are provided to move the levers in opposition to the spring, such means being generally indicated at 21, said numeral designating a controller composed of two taper members mounted on reciprocating rack 22 which derives its motion from pinion 23. The taper members engage rollers 24 carried by levers 15 and 16 and are guided by rollers 25 mounted on the framework independently of 15 the levers.

26 indicates a spool shaft carrying one or more spools 3 and 27 is another spool shaft carrying one or more spools 28. Spools 3 and 28 are located opposite to each other with an intervening 20 spinnerette 1, so that when one spool is filled the thread from the spinnerette may be transferred from one spool to the other. Drive shaft 9 rotates shaft 26 and shaft 10 rotates shaft 27 in this case by the following mechanism. 29 and 30 indicate two auxiliary shafts, one of which is geared to shaft 26 by spiral gears 31, and the other of which is geared to shaft 27 by spiral gears 32. Intermediate shafts 9 and 29 are a set of spur gears 33 having a clutch 34, and a train of spur 25 gears 35 having a clutch 36 extends between shafts 10 and 30. It will therefore be seen that one set of spools 3 is driven from shaft 9 and the other set of spools 28 from shaft 10, and that the speed of the spools will vary in accordance with 35 the speed of rotation of pulleys 11 and 12.

The pump 2 is driven from the constant speed shaft (7), in the present instance by the following means: mounted on shaft 7 is a pulley 37, and on shaft 38 is another pulley 39, and a belt 40 is 40 trained over said pulleys. It will be understood that this drive between shafts 7 and 38 could be in the form of sprocket wheels and chain or otherwise, but, in the present instance, it is preferred to have the speed transmission means shown so that 45 the speed may be adjusted by bringing the faces of pulleys 37 and 39 nearer to or farther away from each other. It must be borne in mind, however, that there is no automatic variation in speed, so far as this device is concerned. Shaft 38 trans- 50 mits motion to pump 2 by any suitable means such as the flexible driving connection indicated at 41.

Suitable means are provided to drive pinion 23 which, in this instance, take the following form: 55

main shaft 1 transmits motion to a shaft 42 by means of chain 43 and suitable sprockets, and shaft 42 in turn drives a shaft 44 by means of pinion 45 and gear 46. Mounted eccentrically of shaft 44 is a pawl 47 that engages and drives a ratchet 48 and engaging with this ratchet is a detent or stop pawl 49. Ratchet 48 is mounted on stub shaft 50 and has an eccentric portion 51 and mounted therein is a housing 52 that reciprocates in guides 53 in response to rotation of eccentric portion 51 of ratchet 48. 54 and 55 indicate two ratchets, fastened together as at 56, and mounted loosely on the end of shaft 50. Means are provided for rotating said ratchets 54 and 55 in either direction, said means being here as follows: carried by reciprocating housing 52 are two sets of pawls that engage ratchets 54 and 55 and thus drive the latter by reason of the reciprocating motion of housing 52. 57 indicates a pivot on housing 52 and on this is mounted a pawl 58 and another pawl 59. It will be seen that these pawls operate in reverse direction and that the teeth of ratchets 54 and 55 are in reverse relation to each other, pawl 58 being adapted to engage ratchet 54 and pawl 59 being adapted to engage ratchet 55. Therefore by throwing in one pawl or the other the ratchets (being secured together at 56) will turn in one direction or the other. Suitable stop pawls 60 and 61 for ratchets 54 and 55 are pivoted at 62 on housing 52, and pawls 58 and 60 are connected together by link 63, and pawls 59 and 61 are likewise connected by means of a link 64. It may also be mentioned here that stop pawl or detent 49 is likewise pivoted to housing 52 at a point indicated at 65 and is normally urged into engagement with ratchet 48 by weight 66. Carried by ratchets 54 and 55 is a pin 67 that transmits motion through pin gear 68 to shaft 69 and this latter in turn drives pinion 23 through suitable reduction gearing.

Suitable means are provided for throwing in or out, with respect to ratchets 54 and 55, either set of pawls. In the present instance these means take the following form: 70 is an interlocking bar pivotally mounted at 71, and 72 and 73 indicate two levers pivoted at 74, one of which controls pawls 58 and 60 and the other of which controls pawls 59 and 61. 75 and 76 indicate two links that extend between interlocking bar 70 and levers 72 and 73. It will now be apparent that, when interlocking bar 70 is in the position shown in Figs. 3 and 4, the free end of lever 72 will be in a lowered position and consequently pawls 58 and 60 will be in engagement with ratchet 54 and will effect rotation thereof in one direction. It will further be apparent that the position of interlocking bar 70 shown in Figs. 3 and 4 will raise the outer free end of lever 73 thereby moving pawls 59 and 61 out of engagement with ratchet 55. When the position of interlocking bar 70 is reversed, it will be obvious that pawls 58 and 60 will be moved out of engagement with ratchet 54 and that pawls 59 and 61 will be moved into engagement with ratchet 55, and as a result ratchet 55 will be driven in the reverse direction from that in which ratchet 54 was driven. It will be remembered that ratchets 54 and 55 are secured together at 56, and it will therefore be seen that driving pin 67 will be moved in one direction when ratchet 54 is engaged by its pawls and in the other direction when ratchet 55 is engaged by its pawls. Consequently pinion 23 will be moved in one direction under one set of conditions, and in the other direction under the other set of conditions, and

as a result rack 22 will be moved up or down in response to the direction of rotation of pinion 23.

When doffing the thread say from spool 3 to spool 28, it is important that both spools should be rotating at the time of transfer of the thread from 3 to 28 as otherwise there will be an accumulation of unwound thread. Suitable means are therefore provided to compel the operator to throw in clutch 36 before he can throw clutch 34 out and vice versa. It is also important that at the same time the action of the ratchet mechanism 54—55 should be reversed. Any suitable means may be provided to accomplish this, but in the present instance the construction is as follows: 77 and 78 represent two latches or pins 15 that work oppositely, that is to say when one is in an upper position the other is in a lower position. When 77 is in an upper position (Fig. 3) it will be seen that it comes in front of an arm 79 attached to clutch lever 80. 79 and 80 are 20 pivoted on center 81, and, should the operator now attempt to declutch 34, pin 77 will prevent such action. Arm 84 is connected in a way similar to that just described to clutch lever 82 pivoted at 83, and both pins 77 and 79 are carried by interlocking bar 70 in such a way that when one pin is up the other is down. It will now be apparent that, with the parts in the position shown in Figs. 1 and 3, the operator cannot declutch 34 unless he first moves clutch 36 into 30 engagement and reverses the position of the pins, thereby at the same time reversing ratchet mechanism 54—55.

The means to reciprocate thread guide 4 are not shown in detail, but it may be pointed out 35 here that such means can be actuated from shaft 85 which latter is driven from main shaft 1 by means of flexible drive 86.

The operation of the device is as follows: let us assume that the parts are in the position shown 40 in the drawings, from which it would appear that the winding operation as regards spool 3 is approaching completion. In these circumstances, it will be seen that clutch 34 is in and cannot be declutched on account of the position of pin 77 45 which prevents lever 79 and therefore clutch lever 80 from being moved to throw out clutch 34. Clutch 36, on the other hand, is out or disengaged. The position of interlocking bar 70 is such that ratchet 54 is being engaged by its driving pawl 58, and rack 22 is rising and has nearly come to the end of its stroke. Said rack, in rising, has gradually separated the faces of pulley 12 and brought the faces of pulley 11 closer together, the result being that the speed of shaft 55 9 has been gradually reduced and that of shaft 10 gradually increased. Spool 3 has therefore been gradually slowed down to compensate for its increase in surface speed. Spool 28 is not being driven at this time because clutch 36 is disengaged. If the operator now desires to discontinue the winding operation with respect to spool 3 and to begin winding on spool 28, he will first of all engage clutch 36 thereby rotating spool 28. He will then transfer the thread from spool 3 to 60 spool 28 and at the same time he will reverse the position of interlocking bar 70 thereby withdrawing pin 77 so that clutch 34 can be declutched, and also thereby reversing the ratchet 65 drive through the connections described, so that pawl 58 no longer engages ratchet 54 and bringing pawl 59 into engagement with ratchet 55. It will be understood that the effect of this is to 70 reverse rotation of pinion 23 and to thereby cause 75

rack 22 to begin its gradual descent. The effect of this is to gradually bring the faces of pulley 12 toward each other and the faces of pulley 11 away from each other. Consequently the speed of shaft 10 and therefore of spool 28 will be gradually reduced while that of shaft 9 will be gradually increased. The operator is now free to withdraw clutch 34 whereby rotation of spool 3 ceases, and he will thereafter remove said spool 10 and substitute an empty one so as to be ready for the next change in the winding operation.

I claim:

In a rayon spinning machine, a spinnerette, two spools either one of which can receive the thread produced by the spinnerette, change-speed transmission means to drive the spools, means to connect or disconnect either spool from the transmission means, latching means to prevent the disconnecting of one spool from the transmission means unless the other spool has been connected to the driving means, and means to reverse the action of the change-speed means when releasing the latch. 5

JULIUS BRENZINGER.
